UNITED STATES PATENT OFFICE

2,250,492

SUPERCHARGED TWO-CYCLE ENGINE

Lauritz N. Miller, Eugene, Oreg.

Application October 12, 1939, Serial No. 299,095

4 Claims. (Cl. 123—74)

This invention relates to a 2-cycle engine which may be of the internal combustion type utilizing gasoline or kindred fuels or which may be of the type using crude oil, fuel oil, and the like, in that event being comparable to the so-called Diesel engine.

The basic principles of the invention, however, are such that the engine will operate on other fuels, such as synthetic fuels, and the like, wherein said fuels in burning, expand gaseously for useful work, the force of such expansion being applied to the power transmitting mechanism through a movable member of the expansion chamber, conventionally illustrated herein as of piston character.

While the invention is primarily directed to the utilization of liquid or vapor fuels, it is not necessarily restricted thereto but by proper additions to the basic disclosure, the engine can accommodate pulverized fuel of a combustible nature for the generation of an expanding gas, or gases, for the derivation of power therefrom by reason of such expansion.

Since the internal combustion engine is almost universally understood as to operation and construction, the present invention is shown incorporated in an embodiment adapted for utilizing liquid fuel and more especially of the gasoline type. By the term "gasoline" however, it is not to be understood that other vaporizable fluids are excluded and as will hereinafter be pointed out, the invention is easily applicable to the utilization of heavier liquid fuels, commonly employed in Diesel engines, by substituting a fuel supply of the aforesaid character for the conventional carburetor or vaporizer utilized in the so-called gasoline engine.

The chief object of the invention is to provide an engine wherein a 2-cycle form of operation is utilized but which is modified so that substantially all the advantages of 4-cycle operation are obtainable therefrom.

The chief feature of the invention consists in the provision of a fuel receiving cylinder, a piston therein, an exhaust arrangement at one end, an intake arrangement at the opposite end, and valve means associated with each arrangement and controlling exhaust from the said cylinder and fuel supply to said cylinder, the piston being of a control valve type, as hereinafter more fully pointed out.

Other objects and features of the invention will be pointed out more fully hereinafter.

The full nature of the invention will be under-

stood from the accompanying drawing and the following description and claims:

In the drawing,

Fig. 1 is a central sectional view of one embodiment of the invention showing the same as an overhead type engine of gasoline fuel consuming character and air cooled.

Fig. 1A is a view of one of the counterbalanced cheeks, of which two are provided, for the throw portion of the crankshaft.

Fig. 2 is a sectional view of the intake valve operating arrangement.

Fig. 3 is a similar view of the exhaust valve operating arrangement.

Fig. 4 is a sectional view of the upper portion of another embodiment of the invention showing the same as of L-head type and of water-cooled type.

In Fig. 1 of the drawing there is illustrated a crankcase structure 10 which may be suitably supported in any desirable manner, herein the same being shown provided with a base bracket arrangement 11. The desired number of bracket arrangements may be employed or may be otherwise positioned, it being understood, of course, the engine is primarily supported through the crankcase structure. The lower end of the crankcase is provided with a conventional drain arrangement 12.

Mounted in the upper portion of the crankcase is a guide arrangement 13 which is relatively elongated and to which reference will be had more fully hereinafter. Herein the same is shown as of cylinder type but it is not necessarily restricted thereto but may be a way structure. Slidably supported therein is a crosshead or guide member 14 and the same mounts a wrist pin 15, in turn pivotally supporting one end of a connecting rod 16.

The opposite end of the connecting rod projects beyond the lower open end 13a of the cylindrical guide arrangement and is pivotally connected as at 17 to a walking beam arrangement 18. This walking beam arrangement at its opposite end is pivotally connected as at 19 to a link structure 20, in turn pivotally mounted as at 21. The walking beam is also pivotally mounted as at 22, intermediate and approximately midway between pivots 17 and 19, on the throw or eccentric portion 23 of a crank shaft 24 and the cheeks 25 of said crankshaft are extended as at 26 opposite the throw portion 23 and constitute a counterbalance arrangement, thus providing for dynamic balancing of the shaft.

It is to be noted that this link, connecting rod,

walking beam and crankshaft construction is illustrated and described in the prior Miller Patent No. 2,005,000 and no claim specific thereto is made herein. The aforementioned patent discloses that the pivot, equivalent to pivot 21, is of eccentric type and adjustable or variable. It also discloses but does not illustrate that this pivot may be of fixed axis character.

Herein pivot 21 is of fixed axis type but it is to be expressly understood that if desired, an eccentric arrangement, as illustrated in the aforesaid patent, may be incorporated for a variable axis type pivot, depending upon the type of power application or performance to be derived from the engine. The pivot 21 if of variable axis type, may be manually or automatically adjusted, as illustrated, described and claimed in the co-pending application, Serial No. 199,210, filed March 31, 1938, and entitled, "Differential convertible gasoline-Diesel engine."

Briefly, in said application, manual adjustment of this axis permits the engine to be initially utilized on a readily vaporizable fuel, such as gasoline, the engine operating as an internal combustion engine of the gasoline type and then being transformed to a Diesel type engine utilizing heavier fuels and operating on a greater compression ratio, it being obvious that by shifting this axis the zero volume of the engine arrangement will be varied resulting in different compression ratios suitable for operation on different fuels and of the different types disclosed. This feature is mentioned herein but not claimed because it is disclosed and claimed in the aforesaid application. It is mentioned herein to point out specifically the possible variations in adaptation of the invention proper herein disclosed and claimed, and such application is specifically made a part of this application insofar as the variable axis and adjustable compression ratio changes are concerned.

In substantially all 2-cycle engines, it is customary to utilize the crankcase as a part of the engine intake system. The present invention specifically differs therefrom in that—see Fig. 1—the crankcase is sealed, as it were, from the cylinder structure, hereinafter to be described. Such seal is indicated by the numeral 30 in Fig. 1 and such seal is split and press-fitted into the remote or exposed end of the cylindrical guide arrangement. It is provided, however, with the bore 31 which slidably supports a stem 32 at its lower end rigidly connected or integral with the crosshead arrangement 14.

In Fig. 1, the numeral 33 illustrates a cylinder which, being of air cooled type, is provided with heat radiating fins 34. The lower end of this cylinder arrangement is provided with an enveloping intake chamber arrangement 35 communicating at regular or any other desired intervals by means of ports 36 with the lower end of the cylinder. These ports are, however, positioned slightly remote from the extreme end of the cylinder for a purpose hereinafter to be described.

The chamber 35 is extended as at 36 and the same communicates with a passage 37 herein shown formed in and as a part of the crankcase although it need not necessarily be so formed. This communication between chamber 36 and intake passage 37 is controlled by an intake valve 38 of poppet valve type, having the stem 39 slidably supported in the guide 40, said stem carrying a spring retainer 41 with which is associated a pair of springs 42 and 43. This valve stem may

5 be suitably actuated at the proper time to open the valve and provide free communication between chamber 35 and the intake passage 37, the valve being positively closed and held closed by the said springs.

Reference now will be had to Fig. 2 wherein a conventional form of valve lift or operating mechanism is illustrated. Herein the numeral 44 indicates a cam member or portion which is adapted to cooperate with a valve lifter sleeve 45 slidably supported in a guide arrangement 46 in the crankcase structure. The sleeve 45 includes an extension 45a against which bears the depending end of the valve stem 39.

As shown in Fig. 1, the intake valve stem is aligned with the crankshaft axis and accordingly, if desired, this intake valve may be actuated by a cam on the crankshaft. This is the simplest form and is readily adapted to single cylinder engine construction. For multiple cylinder engine construction, as is the practice and it is so intended herein to utilize a separate cam shaft for the several intake valves in preference to providing the crankshaft with a plurality of the intake valve operating cam portions. However, it is to be noted that contrary to the 4-cycle engine construction conventional today in automotive engines wherein the cam shaft operates at half crankshaft speed, this crankshaft of necessity must operate at crankshaft speed.

While the invention herein has been illustrated as embodying a poppet valve control for the intake chamber arrangement, it is to be understood that other valve type controls may be employed in lieu thereof and any valve arrangement operable cyclically, as herein disclosed, may be substituted and utilized without departing from the broader features of the invention.

The upper end of the cylinder 33 is closed in a conventional manner by a detachable head structure indicated generally by the numeral 47. It includes therein an exhaust arrangement or chamber 48 and an exhaust passage 49. These two communicate and such communication is controlled by suitable valve means herein illustrated as of poppet valve character and indicated by the numeral 50. The poppet valve includes the stem 51 and the same carries a retainer 52 with which is associated the springs 53 and 54 interposed between the head and such retainer and normally constraining the exhaust valve to closed position. This exhaust valve herein is shown as of rocker arm operable type, the head supporting a bracket 55 which pivotally supports at 56 a rocker arm 57, the latter being actuated by a push-rod 58—see Figs. 1 and 3.

The push rod 58 is constructed somewhat similar to the valve lifter shown in Fig. 2. It is also 60 operated by a cam 59. As shown in Fig. 1, the push rod 58 is offset slightly from the axis of the crankshaft. However, it is to be understood that the rocker arm structure may be so arranged that the push rod intersects the axis of the 65 crankshaft and a cam thereon, such as indicated at 59, will operate said push rod to tilt the rocker arm clockwise in Fig. 1 in opposition to the springs 53 and 54 to open the exhaust valve at the proper time.

As previously set forth, any other valve suitable for the purpose may be substituted for the aforesaid poppet valve and any other drive arrangement as previously set forth, may be utilized, it being noted in multiple cylinder constructions a single camshaft separate from the crankshaft is

utilized and provided with the cams for the intake and exhaust valves of each cylinder properly spaced for the desired timing. Herein such a camshaft would have the same speed as the crankshaft.

All the advantages of multiple cylinder and 2-cycle engine practice are well known insofar as overlapping power impulses are concerned. It is, of course, to be understood that an engine of this character is provided with a flywheel arrangement. This conventional element, however, for simplicity has been intentionally omitted from the drawing. Since this is an air cooled engine, the head structure also is finned as at 60 for heat dissipation or cooling purposes.

Within the cylinder 33 is a piston structure 61 provided with suitable rings 62 conventional to internal combustion engines. Any desired number and type of said rings may be employed. The piston is provided with a stem 32, before 20 mentioned, and said stem may be rigid with, as herein illustrated, or integral with, as herein illustrated, the said piston. This stem is elongated and is slideable in the seal means 30. It is rigidly connected, as stated, to the crosshead 14 or guide 25 member slideable in the guide arrangement 13 in the crackcase 10. The piston, as will be noted from Fig. 1, is of relatively short length compared to automotive engine pistons and more especially to so-called 2-cycle engine pistons, it being inherent in the conventional 2-cycle engine construction heretofore, to provide a long skirt on said piston. The same herein is unnecessary.

It is well to point out that the position of the ports 36, these being the intake ports to the cylinder, with reference to the intake end of the cylinder is such that the piston 61 when at the end of the power stroke may completely uncover said ports and provide free communication between the intake arrangement and the cylinder on the power side of the piston.

It is to be observed also that the construction of the block including the cylinder, is such that the intake arrangement or chamber 136 freely communicates with the lower and intake end of the cylinder on the bottom of the piston, this communication being indicated by the numeral 62.

It is also to be noted—see Fig. 1—and indicated by the dotted line in turn indicated by the 50 numeral 63, the lower end of the chamber 35 is of sloping character and insures surplus fuel drainage to the intake valve port or seat. This is to prevent flooding. The stem structure 32 is herein shown provided with an elongated chamber and, therefore, is of hollow character. The chamber is indicated by the numeral 64 and is closed by a plug structure 65 which herein is shown positioned in the head of the piston and it may have any desired exterior, as desired, and found suitable to facilitate combustion, swirling of the gases, et cetera, well known in the internal combustion engine art.

Within this chamber there is provided the desired amount of material, the same being indicated by the numeral 66 and representing a mixture of lithium nitrate and potassium nitrate. While this is introduced as a powder, under heat the same becomes a liquid and the purpose thereof is to insure cooling of this stem and the piston, 70 it being understood that the same does not fill the entire chamber. On the firing stroke of the piston when there is the greatest heat on the working face of the piston, due to inertia this liquid is at the upper end of this chamber and abstracts 75

heat from the piston and carries it downwardly as the liquid moves to the lower end of the chamber and as will be pointed out hereinafter this heat is transferred to the lower portion of the 5 stem and there dissipated.

There is provided also in the head, as indicated at 67, a spark plug 68. This may be otherwise positioned as desired or required. It is, however, exposed in the zero volume portion of 10 the combustion chamber and is arranged so that piston movement does not interfere with its operation. Since this invention has been illustrated as applied to a gasoline engine, the numeral 69 indicates a conventional carburetor, the conventional controls thereof being intentionally omitted and this carburetor is supplied with fuel from the reservoir 70 or any other suitable source of fuel conventional to gasoline engine practice.

In the preferred form of the invention, the 20 stem 32 is rigid with the piston and guide member. It may, however, be otherwise connected thereto as by a member which is pivotally connected at opposite ends to the piston and the guide member. If desired, such last mentioned pivotal connection may be coaxial with the connecting rod connection for simplicity, thereby requiring but a single wrist pin arrangement at the guide connection. At this point, the operation will be briefly set forth.

If a combustible charge is assumed to be in the exhaust chamber and zero volume arrangement, the exhaust valve 58 being closed, and the piston being at the end of its compression stroke, the plug 68 is energized to ignite the combustible mixture if the fuel is of that character. If the fuel be not of that character, a preheating plug for oil engine operation might be utilized or if the fuel is of the high pressure character, common to Diesel engine practice, the fuel would ignite spontaneously when the piston reaches the upper end of its compression stroke. Upon the fuel igniting, burning and expanding, the piston moves downwardly for work purposes. As the piston moves down, it compresses the fuel in the intake chamber arrangement until the piston seals the ports 36 and as long as such seal is affected, compression is continued because as illustrated by the dotted lines in Fig. 1, the piston continues beyond the intake port sealing position. The exhaust valve is so timed that either prior to the sealing or the unsealing of the intake ports, the zero volume chamber of the exhaust arrangement 48 is in free communication with the exhaust pipe or conduit 49 and these burned gases being under considerable pressure and passage 49 being substantially at atmospheric pressure, the gases immediately discharge.

If the exhaust valve timing is such that it is open for a short interval while the intake 60 ports 36 are open to the cylinder, then a scavenging effect is obtained by the incoming compressed intake charge. If, however, the exhaust valve is closed prior to the opening of the intake ports to the cylinder by continued downward piston movement, there will be no scavenging effect, and, therefore, no dilution of the incoming charge. When the ports 36 are uncovered, it is quite apparent the compressed charge in the intake arrangement rushes into the cylinder and fills the same with a combustible mixture. The piston upon cutting off these intake ports in the upward or return stroke, thereupon compresses this fuel charge until at or near the end of the compression stroke. It is then ignited and the cycle is repeated.

The intake valve 38 is so timed as to operation that immediately upon the piston on its so-called return or compression stroke unsealing the ports 36, the valve is opened and the combustible mixture is supplied from the intake passage 37 to the intake chamber 35. It passes into the cylinder behind the non-working face of the piston through the ports 36 and through the communication 62, and thus abstracts heat from the stem 32 and from the piston and from the cylinder wall, thus being preheated during this stage. Upon the compressed charge of fuel being fired, ignited, et cetera, and the piston returning on its working stroke, this preheated, subsequent fuel charge is compressed as the piston approaches the intake ports 36, it being understood the intake valve 39 preferably is closed immediately prior to the initiation of the return stroke of the piston.

It also will be noted that on precompression of the subsequent charge that such pressure is supplementary to the springs 42 and 43 for seating and maintaining the intake valve in seated relation. It also will be noted that during the compression and the working strokes, the compressing expanding gases are imposed on the exhaust valve and supplementing the springs 53 and 54 to maintain the exhaust valve in closed-seated relation. Thus, the pressures produced in the engine are supplemental and not complementary or opposed to the valve springs, thereby insuring longer valve spring life.

It will be understood, of course, as has been previously suggested hereinbefore, that the stroke of the piston can be regulated and, therefore, the timing with relation to the intake ports for scavenging and degree thereof or the absence of scavenging can be readily obtained as well as the ability to rapidly transform the engine from a gasoline to a Diesel type with a different compression ratio.

In Fig. 4 a modified form of the invention is illustrated and it is merely supplied to illustrate the adaptation of the major or basic presentations of the present invention to an L-type engine and the water-cooled type engine. In said Fig. 4, the valve stem is indicated by the numeral 161, the piston by the numeral 161, the cylinder by the numeral 133, the head by the numeral 167, the same being of water-cooled type having the water jacket portion 160. The exhaust passage is indicated by the numeral 149, the exhaust valve herein is shown in inverted relation but still of poppet valve type and is indicated by the numeral 150, the stem 151 thereof being normally constrained to valve seated position by the spring 153 retained by the retainer 152 on said stem. The exhaust chamber arrangement 148 is in the head and the communication between 148 and 149 is by way of the valve 150. The cylinder is water jacketed as at 134. The operation of this form of the invention is identical to that previously described for the engine illustrated in Fig. 1.

Reference now will be had to Fig. 1 wherein there is illustrated an addition feature. Herein the link 20 pivoted at 21 is shown provided with an offset portion 120 and the link is relieved as at 121. The crankcase is provided with a guide arrangement 100 and slidably mounted therein is an operating member 101 which may be or may not be provided with a spring for constraining it to proper position. The lower end of said member 101 is enlarged into substantially spherical form as at 102 and the same

is seated in a socket portion 103 provided in the enlargement 120 of the link 20. In the reciprocation of the piston it will be remembered the walking beam oscillates resulting in oscillation of the link 20 and this oscillation naturally secures reciprocation of the member 101.

This reciprocation of said member may be employed for either of two purposes, to-wit, it may actuate a Diesel engine injector release arrangement for supplying Diesel engine fuel to the passage 37, or it may be injected into the combustion chamber 48 through a delivery nozzle such as is commonly used in Diesel engine operation. If the engine be of gasoline engine type, this actuating member 101 may be utilized to insure proper timing of the ignition and operation thereof.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In an internal combustion engine, the combination with a cylinder, a piston reciprocable therein, a connecting rod operatively connected at one end to the piston, a crankshaft, a walking beam carried thereby and connected at one end to the rod for crankshaft movement, a link connected at one end to the other end of the beam and pivotally supported at the opposite end, and means movable by and with the link movement for engine operation control.
2. In an air cooled engine, the combination with a cylinder having external fins thereon, an exhaust at one end, and an intake adjacent the opposite end, of a skirt type piston in the cylinder, a stem rigid therewith and a closure for the intake end of the cylinder and slidably supporting said stem, said closure including a cylinder directed enlargement forming an elongated bearing for the stem, and nesting in the skirted portion of the piston, the intake including a plurality of ports adjacent the closure end of the cylinder, a chamber thereabout and independent of the cylinder and freely communicating with the cylinder through the ports for cylinder charging and cylinder and piston cooling when the piston is at the intake end of the cylinder and for cylinder and piston cooling and combustible mixture intake for subsequent pre-compression when the piston is at the exhaust end of the cylinder.
3. In an internal combustion engine, a cylinder, a power piston therein, an elongated stem or rod rigid therewith and having an elongated chamber therein, and heat transferring fluid means in said chamber and movable from end to end thereof in piston movement for piston cooling, the combination of a connecting rod, a crankshaft, a walking beam intermediately carried by the crank portion thereof and connected at one end to the rod, a guide arrangement in alignment with the cylinder, an elongated stem rigid with the piston, guide means in said guide arrangement and carried by the stem, the connecting rod having pivotal connection with the guide means, and a link pivoted at one end upon a stationary axis and at its opposite end to the other end of the walking beam for the purpose set forth.

4. In an internal combustion engine, a cylinder, a power piston therein, an elongated stem or rod rigid therewith and having an elongated chamber therein, heat transferring fluid means in said chamber and movable from end to end thereof in piston movement for piston cooling, the combination of a connecting rod, a crankshaft, a walking beam intermediately carried by the crank portion thereof and connected at one end to the rod, a guide arrangement in alignment with the cylinder, an elongated stem rigid with the piston, guide means in said guide arrangement and carried by

10

the stem, the connecting rod having pivotal connection with the guide means, a link pivoted at one end upon a stationary axis and at its opposite end to the other end of the walking beam for the purpose set forth, engine control means supported adjacent said stationary axis, and means carried by the link adjacent its stationary axis pivotal support and having operative engagement with the control means for engine control when operating as a gasoline and a Diesel engine substantially as described.

LAURITZ N. MILLER.
